SLIP

Loretta Novy, St. Louis, Mo., assignor to Weil-Kalter Manufacturing Company, St. Louis, Mo., a corporation of Missouri

Application May 19, 1944, Serial No. 536,266

1 Claim. (Cl. 2-73)

1

The present invention relates to a slip.

It is an object of the invention to provide a slip having bust portions designed to give individual support in combination with a snugly fitting midriff portion.

A further object is to provide a combination of bust portion and midriff portion that does not restrict the type of brassière used or destroy the moulding effect produced by the chosen type of brassière.

A more particular object is to provide a combination of bust portion, back portion and midriff portion in a slip, giving a snug midriff with a high waist and a bust portion designed to give full effect to the bust moulding produced by the selected brassière.

In the drawing:

Fig. 1 is a front view of the slip;

Fig. 2 is a rear view of the slip;

Fig. 3 is a vertical section taken on the line 3-3 of Fig. 1; and

Fig. 4 is a section on the line 4-4 of Fig. 2.

The slip includes a front skirt portion 10, and a rear skirt portion 11 joined at seams 12 and 13. Both of the two panels 10 and 11 are cut on the straight. This has the advantages that they maintain a fixed hem line, and do not creep.

The front panel 10 has a pointed upper edge curving downwardly from approximately the waist line at the sides, to a center point at 14.

The rear panel has an upper edge 15 disposed at approximately the waist line.

The midriff panel 16, cut on the bias, has its lower edge pointed to conform to the upper edges on the front skirt portion 10, and is stitched thereto, forming the seams 17 and 18, meeting at the point 14. The midriff panel 16 extends to the rear approximately as far as does the front panel 10. The upper edge of the midriff panel 16 consists of two parts 20 and 21 disposed above the waist line and curving upwardly in the middle to a point at 22.

Two bust panels 23 and 24 have lower edges cut as shown to fit on the upper edges of the midriff panel 16. They are stitched to the upper edges 20 and 21 of the midriff panel 16 in a surplice manner. The bust panels 23 and 24 are cut on the bias. It will be observed that the bottom edge of the members 23 and 24 are secured to the midriff section across the point 22, and that the two bust portions 23 and 24 are not otherwise connected together at the middle of the garment.

The bust panels 23 and 24 have inner upper edges 26 and 27, as shown. These two edges pro-

2

vide a V neck. The outer portion of the upper edges of the bust panels 23 and 24 slope downwardly, as shown at 28 and 29.

The back of the garment is formed with two upper back panels 30 and 31. These panels are joined together at a mid-seam 32 and are joined to the upper edge 15 of the rear skirt panel 11. The lateral edges of the panels 30 and 31 are joined to the side edges of the midriff section 10 and the two bust panels 23 and 24. The upper edges 33 and 34 of the rear upper panels form continuations of the downwardly sloping edges 28 and 29 of the bust panels 23 and 24.

Shoulder straps 37 and 38 extend from the top of the bust panels 23 and 24 to the top edge of the back panels.

The bust portions are provided with darts to give the right shape thereto.

The fact that the skirt portions 10 and 11 are cut on the straight reduces the creeping as heretofore mentioned. However, provision must be made for expansion at the waist of the garment so that it can be put on. The midriff panel 16, cut on the bias and with its depending point 14, provides for this expansion from the waist downwardly toward the hip section. The garment may expand laterally until the edges 17 and 18 form substantially a straight line and thereby the wearer may get into the garment by pulling it over the head.

The fact that the midriff section is cut on the bias and, more particularly with the aid of the upper back panels 30 and 31 cut on the bias, provides a garment that fits snugly at the waist.

The surplice design of the bust portion allows the brassière to do the moulding. Many slips superimpose certain moulding action over that of the brassière, due in part to junction or merging of the two front bust panels, which eliminates the individual shaping that is permissible with the present garment having its surplice front construction.

Further, the present construction with its bias bust panels cut in surplice manner and secured, as shown, to a shaped and snug midriff section provides a garment that does not draw in a direction from each shoulder strap down. Therefore, this slip does not depress any upward moulding provided by the brassière.

The garment also provides for a low neck line which may be lowered to even an exaggerated condition by lowering the shoulder straps.

It will be noted that the waist line is high in this slip. The midriff panel 16 is substantially wholly above the waist line. Consequently, some

lowering of the shoulder straps is quite permissible without materially altering the fit of the garment.

What is claimed is:

In a slip, a skirt extending from a waist portion down to a hem line, said skirt portion having an upper edge substantially at the waist of the wearer, a laterally yieldable midriff section extending across the front of the garment to the sides thereof, attached to the upper edge of the waist portion extending upwardly therefrom to provide an upper edge just below the bust of the wearer, means across the back of the garment connecting the lateral ends of the midriff sec-

tion, said midriff section and connecting means being adapted yieldably to fit the waist of the wearer snugly and provide support for the skirt from the waist of the wearer, a pair of bust panels extending upwardly from the upper edge of the midriff section, each of said bust panels having a lower edge secured to the said upper edge, the said lower edges of the bust panels overlapping at the middle of the midriff section but being otherwise independent of one another so that they may independently mold to the bust of the wearer, and means for supporting the upper parts of said bust panels.

LORETTA NOVY.
